UNITED STATES PATENT OFFICE

WERNER UEBERMUTH, OF BERLIN-OBERSCHONEWEIDE, GERMANY, ASSIGNOR TO
GENERAL ELECTRIC COMPANY, A CORPORATION OF NEW YORK

VALVE SYSTEM

Application filed May 10, 1930, Serial No. 451,388, and in Germany May 18, 1929.

My invention relates to valve systems, and more particularly to valve systems for the rapid control of pipe lines containing gas under pressure.

5 It is an object of my invention to provide a system of this type which is operated rapidly and by a very small force and nevertheless exposes a large area.

To this end I design the valve as a stepped piston and provide for the regulation of the pressure on one side of the main valve a control valve which is a duplicate of the main valve on a reduced scale.

In a stepped piston valve of the kind described the valve is held on its seat by a force which is proportional to the differential area of its two faces, when equal pressure acts on both faces. When the pressure acting on the larger face is relieved or reduced, preferably 20 by connecting it with atmosphere, the piston valve is unseated by the excess of pressure acting on its smaller face.

If the pressure acting on the piston valve is high and the force available for venting is 25 high, the space connected with its larger face is small, the control valve must be small in proportion so that it is unable to rapidly relieve the pressure on the larger face. In order to control the valve at a faster rate I 30 provide the control valve referred to, which is a reduced duplicate of, and is similar in operation to the main valve. The control valve, which may be operated directly or indirectly by any suitable mechanism, controls 35 an opening which is so large as to permit rapid venting of the space connected with the larger face of the main valve. As the control valve is so much smaller than the main valve, it is operated rapidly by a small force 40 and a correspondingly rapid reduction of the pressure acting on the larger face of the main valve is the result.

In the drawing affixed to this specification 45 and forming a part thereof a valve embodying my invention is illustrated diagrammatically by way of example.

In the drawing
Fig. 1 is a diagram showing the position of
50 the control valve at a reservoir containing

compressed gas for an arc extinguisher of a gas-blast switch,

Fig. 2 is an elevation, partly in section, showing the main and control valves on a 55 larger scale, and

Fig. 3 is a detail showing a relay in combination with the control valve.

Referring to the drawing and first to Fig. 1, 1 is a reservoir containing gas under pressure for supplying a gas blast to the arc extinguisher, 2 is the casing of the main valve, 3 is a pipe extending from the reservoir to the casing 2, 4 is a pipe extending from the casing to the extinguisher or exhaust pipe 5 through which the aforesaid gas blast is directed, 6 is the casing of the control valve, 7 is a lever for operating the control valve, and 8 is a link connecting lever 7 with an electric mechanism, not shown.

Referring now to Fig. 2, 9 is a piston valve 70 with a large piston 10 which is fitted to slide in a cylinder of the casing 2, and a small piston 11 which controls a seat intermediate the pipes 3 and 4. 12 is a spring in the large piston 10 which tends to seat the valve, and 13 is a small bore or passage which connects the pipe 3 with the cylinder of the piston 10. 14 is a pipe which connects the cylinder with the casing 6 of the control valve. 15 is the control valve which is seated above an opening 16 in the pipe 14 with its smaller piston while its larger piston 17, similarly to the larger piston 10 of the valve 9, is fitted to slide in the casing and is equipped with a 80 spring 18 for seating the valve.

When the control valve 15 is lifted from its seat, the pressure in the cylinder of the piston 10 is relieved rather abruptly on account of the large diameter of the opening 16 so that the excess pressure from the pipe 3 moves the smaller piston 11 from its seat intermediate the pipes 3 and 4. When the control valve 15 is seated pressure builds up in the casing 2, gas being admitted to the cylinder through the bore 13 so that the piston 10, assisted by the spring 12, is moved to the right and the connection between the pipes 3 and 4 is interrupted by the piston 11 becoming seated.

The control valve 15 being a reduced du- 100

plicate of the main valve 9 is operated practically without inertia forces.

The operating lever is seated on a cam shaft 19 with a cam 20, which shaft is fitted 5 to rotate and to slide in the casing 6 and is connected with a piston 21 and a spring 22. The cam 20 cooperates with the spindle 23 of an auxiliary valve 24 which is held on a seat in the casing 6 above the piston 17 of 10 the control valve 15 by a spring 26. 25 is a bore in the casing 6 which connects it with the atmosphere, so that when the cam shaft 19 is rotated to open the valve 24 the space above the piston 17 is connected with the atmosphere through the bore 25, the pressure above the piston 17 is reduced and the valve 15 lays open the opening 16.

It is not desirable that the main valve 9 should connect the pipes 3 and 4 longer than 20 is required but that it should be closed as soon as the desired effect, extinguishing the arc has been achieved. Since arc ing may be quickly extinguished at the proper pressure, a brief gas blast is sufficient. This is effected through the medium of a pipe 27 which connects the space in the casing 6 at the rear of the piston 21 with the pipe 4, so that when gas flows in the pipe 4 the cam shaft 19 is moved to the right and moves the 25 cam 20 out of engagement with the spindle 23. The spring 26 now closes the auxiliary valve 24 whereupon the control valve 15 is seated and causes the main valve 9 to be seated in the manner described.

35 Means are preferably provided for preventing operation of the main valve, when the pressure in the reservoir is too low. To this end a valve 28 is arranged in a suitable casing 29 which may be connected with, or 40 arranged on, the reservoir 1. In Fig. 1, a pipe 30 is shown by which the casing 29 is connected with the reservoir 1. 31 is a spring which tends to open the valve 28, and 32 is a pipe line which connects the casing 29 with 45 that part of the casing 6 in which the piston 21 is fitted to slide. When the pressure in the reservoir 1 falls below the limit for which the spring 31 has been adjusted, the 50 valve 28 is opened by the spring and admits gas from the reservoir 1 to the chamber of the piston 21, forcing it to the right and moving the cam 20 out of connection with the stem of the auxiliary valve 24, so that 55 when the link 8 is operated by the electrical mechanism referred to the valve 24 will not open.

60 Pneumatic or electrical signalling means (not shown) may be provided so as to be operated by the pressure in the pipe 32 and to indicate that the pressure in the reservoir 1 has become too low.

When the pressure in the reservoir has 65 attained its normal amount, the valve 28 closes and the gas from the pipe 32 escapes

through a small bore 33 in the cylinder of the piston 21.

If electrical energy is employed for operating the valve system, the force may be so small that the auxiliary valve 24 cannot be 70 actuated. In such cases the relay mechanism illustrated in Fig. 3 is combined with the valve 24. 34 is a cylinder which is secured to the casing 6 above the chamber of the valve 24, 35 is a piston which is fitted to slide in the cylinder 34 against a spring 36, and 37 is a piston rod which projects from the cover of the cylinder. The lever 7 is arranged in suitable bearings on the cover of the cylinder and is connected with a pawl 38 which is adapted to engage below the shoulder 39 on the piston rod. Spring means, not shown, or any other suitable means, may be provided which tend to hold the pawl 38 engaged with the shoulder 39. The pipes 27 and 32 are connected with the space below the piston 35. When the valve 9 has been operated the pressure from the pipe 27 raises the piston 35 and causes the pawl 38 to engage below its shoulder 39. When the lever 7 is operated by the link 8, the pawl 38 is withdrawn, the piston 35 descends under the action of its spring 36, and the lower end of the piston rod 37 strikes the stem 23 of the auxiliary valve 24. The air from the 85 chamber above the valve is discharged through a bore 40, and the valve 15 is operated as described. When the valve has been operated the pressure in the pipe 27 returns the piston 35 to its initial position in which the rod 37 is arrested by the pawl 38, and the relay mechanism is now ready for the 90 next operation. When the pressure in the reservoir 1 falls below the limit aforesaid, the valve 28 is opened and admits gas to the 95 chamber below the piston 35 through the pipe 32. The piston is now raised and operation of the valve 24 is prevented as the piston cannot descend notwithstanding the release of its rod by the pawl 38.

100 I wish it to be understood that I do not desire to be limited to the exact details of construction shown and described for obvious modifications will occur to a person skilled in the art.

105 In the claims affixed to this specification no selection of any particular modification of the invention is intended to the exclusion of other modifications thereof and the right to subsequently make claim to any modification not covered by these claims is expressly reserved.

110 I claim:

115 1. A valve system comprising a main valve including two pistons of different diameters, a cylinder in which one of said pistons is fitted to slide, a casing connected with said cylinder, a control valve which is substantially a duplicate of the said main valve on a reduced scale and is fitted to slide in said casing and 120 125 130

adapted to relieve the pressure on the larger piston of said main valve, means including an auxiliary valve for relieving the pressure on the larger piston of said control valve, and 5 means influenced by the pressure controlled by said main valve for rendering inactive said pressure-relieving means.

2. A valve system comprising a reservoir for fluid under pressure, a main valve connected with said reservoir and including two pistons of different diameters, a cylinder in which one of said pistons is fitted to slide, a casing connected with said cylinder, a control valve which is substantially a duplicate 10 of the said main valve on a reduced scale and is fitted to slide in said casing and adapted to relieve the pressure on the larger piston of said main valve, means including an auxiliary valve for relieving the pressure on the larger piston of said control valve, and means influenced by the pressure in said reservoir for rendering inactive said pressure-relieving means.

3. A valve system comprising a main valve including two pistons of different diameters, a cylinder in which one of said pistons is fitted to slide, a casing connected with said cylinder, a control valve which is substantially a duplicate of the said main valve on 15 a reduced scale and is fitted to slide in said casing and adapted to relieve the pressure on the larger piston of said main valve, an auxiliary valve for relieving the pressure on the larger piston of said control valve, a spring-controlled member for opening said auxiliary valve and means for locking said member against operation by said spring.

4. A valve system comprising a main valve including two pistons of different diameters, 20 a cylinder in which one of said pistons is fitted to slide, a casing connected with said cylinder, a control valve which is substantially a duplicate of the said main valve on a reduced scale and is fitted to slide in said casing and adapted to relieve the pressure on the larger piston of said main valve, an auxiliary valve for relieving the pressure on the larger piston of said control valve, a spring-controlled piston for opening said auxiliary 25 valve, means for locking said piston against operation by its spring, and means influenced by the pressure controlled by said main valve for moving said spring-controlled piston into a position in which it is held by said locking means.

5. A valve system comprising a reservoir for fluid under pressure, a main valve connected with said reservoir and including two pistons of different diameters, a cylinder in which one of said pistons is fitted to slide, a casing connected with said cylinder, a control valve which is substantially a duplicate of the said main valve on a reduced scale and is fitted to slide in said casing and adapted to relieve the pressure on the larger piston

of said main valve, an auxiliary valve for relieving the pressure on the larger piston of said control valve, a spring-controlled piston for opening said auxiliary valve, means for locking said piston against operation by said spring, and means influenced by the pressure in said reservoir for moving said spring-controlled piston into a position in which it is held by said locking means.

6. A valve system comprising a reservoir for fluid under pressure, a main valve connected with said reservoir and including two pistons of different diameters, a cylinder in which one of said pistons is fitted to slide, a casing connected with said cylinder, a control valve which is substantially a duplicate of the said main valve on a reduced scale and is fitted to slide in said casing and adapted to relieve the pressure on the larger piston of said main valve, means including an auxiliary valve for relieving the pressure on the larger piston of said control valve, a valve connected with said reservoir which is so loaded as to open at a predetermined pressure in said reservoir, and means operated by said loaded valve for rendering inactive said pressure relieving means.

7. A valve system comprising a main valve including two pistons of different diameters, a cylinder in which one of said pistons is fitted to slide, a casing connected with said cylinder, a control valve which is substantially a duplicate of the said main valve on a reduced scale and is fitted to slide in said casing and adapted to relieve the pressure on the larger piston of said main valve, an auxiliary valve for relieving the pressure on the larger piston of said control valve, a cam shaft for operating said auxiliary valve, and means influenced by the pressure controlled by said main valve for moving said cam shaft into inactive position with respect to said auxiliary valve.

8. A valve system comprising a reservoir for fluid under pressure, a main valve connected with said reservoir and including two pistons of different diameters, a cylinder in which one of said pistons is fitted to slide, a casing connected with said cylinder, a control valve which is substantially a duplicate of the said main valve on a reduced scale and is fitted to slide in said casing and adapted to relieve the pressure on the larger piston of said main valve, an auxiliary valve for relieving the pressure on the larger piston of said control valve, a cam shaft for operating said auxiliary valve, and means influenced by the pressure in said reservoir for moving said cam shaft into inactive position with respect to said auxiliary valve.

9. A valve system for controlling a brief gas blast comprising a reservoir for fluid under pressure, a main valve controlling communication between said reservoir and an exhaust passage for said blast, the pressure at

- opposite sides of a piston controlling said main valve being substantially equalized in the closed position thereof, a control valve for relieving pressure on one side of said main valve piston causing opening thereof, and means responsive to the blast pressure within said exhaust passage for causing closing of said control valve and subsequent re-closing of said main valve.
10. 10. A valve system for controlling a gas blast comprising a reservoir for fluid under pressure, a main valve controlling communication between said reservoir and an exhaust passage, the pressure at opposite sides of a piston controlling said main valve being substantially equalized in the closed position thereof, a control valve for relieving pressure on one side of said main valve piston causing opening thereof, means controlling the operation of said control valve, and means forming a fluid passage between said exhaust passage and said controlling means, the pressure transmitted through said fluid passage during the gas blast causing closing of said control valve and subsequent closing of said main valve.
15. 11. A valve system for controlling a brief gas blast comprising a reservoir for fluid under pressure, a main valve controlling communication between said reservoir and an exhaust passage, means for substantially equalizing the pressure on opposite sides of a piston controlling said main valve in the closed position, a control valve for relieving pressure on one side of said main valve piston causing opening thereof, the aforesaid pressure being likewise equalized at opposite sides of a piston controlling said control valve, an auxiliary valve for relieving pressure on one side of said control valve piston, and means responsive to the blast pressure within the aforesaid exhaust passage for causing closing of said auxiliary valve and subsequent closing of said control and main valves.

In testimony whereof I affix my signature.

WERNER UEBERMUTH.
